Inventor Joseph V. Weekbaugh
By his Attorney Kern Page Cooper + Hayward

UNITED STATES PATENT OFFICE.

JOSEPH V. WECKBAUGH, OF NEW YORK, N. Y.

ACCOUNTING MACHINE.

Application filed February 14, 1920. Serial No. 358,772.

To all whom it may concern:

Be it known that I, JOSEPH V. WECKBAUGH, a citizen of the United States of America, residing at New York, in the county and State of New York, have invented certain new and useful Improvements in Accounting Machines, of which the following is a full, clear, and exact description.

This invention relates to improvements in accounting machines, and has for its object the provision of an accounting machine of such character that a very large number of customers' accounts may be kept without the necessity of separate registering counters for each account or a complicated bookkeeping system.

The machine may best be understood by considering the present system used in a retail store to which the machine is more particularly adapted.

In such a store it is the practise to write out duplicate or triplicate sales slips giving the names and prices of the articles purchased and the written total of the amount. One of these slips is usually wrapped with the goods and the other retained for posting or bookkeeping purposes. Certain systems have been devised in which the slips are themselves retained in clips and form the record of the transaction. All of these systems are subject to common disadvantages, namely, that mental addition by clerks frequently results in erroneous totals, and that a lost slip causes an error in the account. The totalizing of any large number of the individual accounts on individual counters has proved impracticable, due to the fact that the number of accounts necessitates an exceedingly multitudinous number of counters with the attendant cost and complication.

In the present invention I provide a machine which comprises two main parts, namely, a computing section and an accounting section.

The accounting section of the machine comprises a cabinet with index consisting of names on the top thereof corresponding to the customers' names or the account names. Positioned adjacent the names are movable index arms which are adapted to be positioned opposite any individual name on the index. Within the cabinet are a number of carriages each containing a number of account carrying members or unit arms.

There is one particular account carrying member or unit arm for each customer or for each account. The machine illustrated provides for 518 separate accounts or customers. The movement of the index arm is adapted to select and position a single unit arm or account carrying member corresponding to the name standing opposite the index arm. After the setting movement has been completed, a further manipulation of the index arm releases the unit arm and causes it to swing up into cooperative relation with the computing section of the machine, in which position the amount of the account carried thereon may be read.

The computing section of the machine is alongside the accounting section and consists of an adding machine of well known type adapted to print items and totals and to also effect subtractions and print the results thereof. The computing section of the machine includes a sales slip carriage which is disposed adjacent the printing mechanism of the adding machine.

The unit arm which is in cooperative relation with the computing section is in such position that the salesman can see the record carried thereby. This arm also is provided with suitable type representing account designating data and preferably giving the name and address of the customer whose account is carried by the particular arm or account carrying member.

With the foregoing brief description of the machine, the mode of operation, the objects, and the method of operating as now set forth will be clearly understood.

It is believed that the best understanding of the objects of the invention will be had by tracing the sequence of operations which take place upon two particular transactions.

The clerk writes out the duplicate sales slip in the usual manner, writing in the items of the sale and the item amounts. The original sales slip is placed in the computing section, the customer's unit arm is selected and brought into cooperation with the adding machine. The salesman then sets up on the adding machine the individual items appearing on the duplicate sales slip. The items are printed opposite the written amounts on the sales slip. Finally the total is printed. Simultaneously therewith is

printed a duplicate record check showing the amounts and totals, this check being retained in the machine. The printing operation also impresses on the sales slip and record check a printed impression showing the customer's name and address. In addition to the printing mentioned above, the total printing operation effects a printing of the total of all the items upon a strip of paper which is cut off by the operation of the machine. This slip or check is termed the total check, and by means of suitable automatically operated mechanism is transferred to the unit arm where it is retained. The final event in the transaction is the release of the unit arm and its return to position in the accounting section.

Upon the next transaction of the same customer the preceding described sequence of operations is followed with the exception that before starting to set up the new items the salesman observes the amount on the total check in the unit arm or account carrying member and sets this amount up first on the adding machine as the amount of the account brought forward. When the new total check is printed, means is provided for releasing the old total check from the unit arm which then receives the new total check.

It will be understood therefore that in the present construction the accounts of the individual customers are carried by small slips of paper in the unit arms. The carrying forward of the account when additional items are to be added or subtracted is effected by the operator setting up on the machine the printed total record displayed before him. This machine therefore can have the capacity to carry a larger number of accounts than would be possible if there were a separate register for each customer. There is in fact no practicable limit to the number of accounts that can be carried, as it is only necessary to provide a greater number of unit arms.

With the foregoing main objects of the invention set forth, I will now describe in detail the machine. This description will also set forth certain other allied objects and advantages of the machine.

In the drawings,

Fig. 1 shows a top plan of the machine showing the accounting sections and the computing section and certain associated parts.

Fig. 2 shows a side view of the adding machine and the accounting section.

Fig. 3 shows a top plan view of the index section of the accounting section with parts broken away to show the top of the carriages.

Fig. 4 shows a sectional view of the accounting section taken on line 4-4 of Fig. 9 and looking in the direction of the arrow.

Fig. 5 is an enlarged detail view of the index carriage and connections to the unit arm carriage brackets.

Figs. 6 and 7 are detail views of the unit arm.

Fig. 8 is a detail showing an index plate.

Fig. 9 shows a sectional view of the accounting section together with certain of the unit arms.

Fig. 10 shows a detail view of the carriage latching devices and releasing mechanism with the parts moved to carriage latching position and unit arm latching position.

Fig. 11 shows a detail view of the means for restoring the locking line and for releasing the carriages.

Fig. 12 shows a detail view of the mechanism at the rear of the adding machine which is associated with the accounting structure.

Fig. 13 shows a detail view of the pawls for retaining the locking line and unit arm setting and carriage setting mechanism. The view is a section taken on line 13-13 of Fig. 12.

Fig. 14 shows a side view of retaining pawls for the locking line and unit arm setting mechanism. This view is taken on line 14-14 of Fig. 12.

Fig. 15 shows a top plan view of the printing mechanism and certain associated parts.

Fig. 16 is a detail view of the total check carriage showing its relation to the unit arm.

Fig. 17 is a sectional view of the unit arm showing check retaining plate and address plate. This is a sectional view taken on line 17-17 of Fig. 16.

Figs. 18, 19 and 20 are detail views of the total check carriage, the sections being taken on lines 18-18, 19-19 and 20-20 of Fig. 16.

Fig. 21 shows a unit arm adjacent the adding machine in position to receive a total check.

Fig. 22 shows the unit arm in a closed position gripping check and also shows certain other associated parts.

Fig. 23 shows a sectional view, taken on line 23-23 of Fig. 12, and shows the record check shearing and feeding mechanism and address printing mechanism. This figure shows sales slip carriage in its extreme upward position.

Fig. 24 is a sectional view taken on line 24-24 of Fig. 12, and shows a detail view of the mechanism for operating the shearing, record check, and feeding mechanism and address printer mechanism. This figure also shows the operating mechanism for the total check shear.

Fig. 25 shows a sectional view of the adding printing segments in their relation to the sales slip carriage, total check carriage and record check. This figure also shows the

escapement for releasing the sales slip carriage.

5 Figs. 26 and 27 show cam mechanism for controlling the feed of the record check by the total key of the adding machine.

Fig. 28 is a front view of the sales slip carriage.

10 Fig. 29 is a sectional view of the sales slip carriage on line 29-29 of Fig. 28, but in open position.

Fig. 30 shows a duplicate record slip.

Fig. 31 shows a duplicate record slip.

15 Fig. 32 shows duplicate written sales slip with the record slip shown in Fig. 31 slipped on the slot therein for filing.

Fig. 33 shows a sales slip with a received on account transaction entered thereon by the machine.

20 Fig. 34 shows a view of a total record check.

Accounting section.

The accounting section and mechanism therein is shown in Figs. 1, 2, 3, 4, 5, 6, 7, 8, 25 9, 10 and 11.

30 In Fig. 1, the accounting section A comprises a casing 50 substantially rectangular in shape having a tray 51 therein (see Fig. 4) which is slotted as shown in Fig. 1.

35 This tray is adapted to receive removable index plates 52, see Fig. 8, into which may be slipped slips of paper bearing the customer's name or other account designating data. The tops of the plates are sloped to facilitate reading. The group of name plates are covered by removable glass cover plates 53. These groups of name plates comprise the index section of the accounting section. The tray 51 is slotted at the left of the 40 groups of indices with slots 54 through which project index arms 55 having, slightly below each index arm and slidably thereby, an index carriage 56 which is supported by rollers 57 on rails 58 which are suitably mounted in the casing (see Figs. 45 and 9). To each index carriage is fastened a pointer 59 cooperating with the index name plates.

50 The normal position of the index arm is at the center of the index section, see Figs. 1 and 3. From this point the arm may be moved freely backward or forward in slots 54. Adjacent each index arm carriage are two supplementary index carriages 61 and 62 (see Figs. 3, 4 and 5). These carriages are adapted to be moved in the direction of the arrows shown in Fig. 3 by the index arms upon a sliding movement thereof. The supplementary carriages are provided with 55 supporting and guiding rollers which cooperate with the rails 58 (see Figs. 5 and 9). Each supplementary index carriage has attached thereto a metal bracket piece 63 which connects with unit arm carriages 64 and 64^a (see Figs. 4, 5 and 9). The unit

arm carriages are grouped closely together in order to avoid excessive length of the unit arm. The unit arm carriages are provided with rollers 65 which rest upon supporting rails 66.

70

There are groups of unit arm carriages 64 at the left, as shown in Fig. 4, and other groups 64^a at the right. The left and right hand groups are mounted upon adjacent rails 66 as shown in Fig. 9. Moving index 75 arm to the right moves supplementary index carriage 61 to the right locking the supplementary carriage to the index carriage by means of gravity pawl 67 engaging a locking pin on the index carriage (see Fig. 5). 80 When the parts are in normal position the pawl is disengaged by abutting against pin 68. Fig. 4 shows in dotted lines the carriage 64 moved to the right. A movement of the index arm in reverse direction moves the right hand carriage 64^a. The carriages are returned to normal position by returning springs 69. It will be understood that the index arm 55 is moved until the pointer 59 stands opposite the desired name on the index section. Each unit arm carriage has a shaft 70 therein which forms a support for a number of unit arms or account carrying members 71. The movement of the carriage is adapted to 90 bring a particular unit arm, corresponding to a particular customer's account, to the dotted line position as shown in Fig. 4. After the index arm 55 has been moved to its proper position the handle 55 is depressed. This movement effects the following operations.

95

The spring plunger 72 is moved down (see Figs. 5 and 10) thereby engaging the end of the plunger in an aligning rack 73 and thereby accurately positioning the carriage and the unit arm. The plunger also impacts against and rocks a bent plate 74 (see Fig. 10). Plate 74 through a pin forces tripping bar 75 to the left against the tension of return spring 76, thereby rocking releasing pawl 77 so as to release locking bar 78 and permits it to move to the left under the tension of a spring 79 (see Fig. 9). The pawl 77^a lies directly behind pawl 115 77 and is best shown in Figs. 13 and 14. The similar and parallel pawl 77^a is also released by the movement of the tripping bar. The locking bar carries a number of pins 80 and these pins are adapted, when the bar is moved to the left, to enter slots 81 in carriages 64, 64^a, etc., and locks the same all in neutral position (see Figs. 4 and 10). In this manner, after a particular unit arm is selected, the unit arm carriage containing that arm and all other carriages whether the one operated by the same index arm or others, are locked and cannot be moved until certain further operations are performed. The locking bar is retained in left-hand po- 120

125

130

sition by means of a locking plate or pawl 82.

The releasing pawl 77, which as previously explained, is directly behind pawl 77 (see Figs. 10, 13 and 14), normally engages a notch in an arm 83 (best shown in Fig. 11). When the releasing pawl swings anti-clockwise under the influence of the leftward movement of bar 75, the arm 83 is released and swings anti-clockwise under the influence of spring 84 (Figs. 10 and 11). This spring 84 is put under tension by the movement of locking bar 78 to the left. The foregoing movement of arm 83 releases pawl 85 from engagement with parallel bar 86 (see Figs. 9, 10 and 11).

The means for swinging the selected account carrying member or unit arm into cooperative relation with the computing machine and into reading position will now be described. The parallel bar 86 is disposed directly over the selected unit arm (see Fig. 4). The movement of the parallel bar to the left and downward is adapted to cause said bar to impact against the curved edge 87 of the account carrying member or arm and to swing the arm counter-clockwise about its shaft as shown in Fig. 10. The curved edge 87 is so designed as to cause a fast initial movement and a slow final movement of the arm. The parallel bar 86 at its ends is pivotally fastened to two links 88, 89, which are pivoted on shafts 90, 91, which also carry segments 92 which are fastened to links 88 and 89 and which mesh with a rack 93 having side plates which are slotted to engage the shafts. The rack 93 moves to the left under the influence of a power spring 94 after the parallel bar is released. This movement of the rack transmits movement through the segments 92 to the links 88, 89 and to the parallel bar 86. The speed of movement is checked by a suitable dash pot 95.

This movement of the parallel bar swings the unit arm or account carrying member up into reading position in the computing machine and in position to discharge the old total check and receive a new one. The unit arm is retained in position by a pawl 96 shown in Figs. 9 and 10.

Computing section.

The parts heretofore described are adapted to swing a particular unit arm to the position shown in Figs. 12 and 15. It will be assumed that this unit arm already carries a total check representing an amount of 104.12. This amount is visible to the operator in the computing section after the unit arm has swung up into position. It will be assumed that the customer whose unit arm shows a total of 104.12 now purchases additional articles. The salesman writes the names of the articles on the original sales

slip (see Fig. 30) together with the item amounts. Similar written data is transcribed to the duplicate sales slip by carbon paper (see Fig. 32). The person operating the machine then places the original sales slip in the sales slip carriage 100 (see Figs. 28 and 29) between the sales slip holder 101 and the back of the carriage. The operator then presses the sales slip carriage down in the machine to the position shown in Fig. 24. The carriage in its downward movement brings a pin 103 into engagement with a cam 104 carried by the sales slip holder and swings the sales slip holder to closed position against the tension of spring 102 (see Figs. 28 and 29). The sales slip carriage is provided with suitable guide rails cooperating with the guides shown in Figs. 27 and 28 and also with a rack 105 which cooperates with a gear 106 having a drum on which is a cable secured to a tension spring 107 (see Figs. 23-24). The downward movement of the carriage tensions this spring. The carriage also carries a carbon ribbon 108 carried on rolls 109 and 110 and adapted to be rewound by turning knob 111. In order to print duplicate item checks or record slips, I provide a strip of paper which is carried by supply roll 112 (see Figs. 23 and 29) and which passes back of the carbon strip over platen roll 113 and between feed rolls 114 and rearwardly to cut off knives 116, 117. The rolls 114 are operated through gearing 115 from sales slip carriage rack 105 during the upward movement of the carriage to advance the paper which forms the record slip. This strip of paper is cut off to form the record slips or checks shown in Fig. 31 and these checks or slips are retained in the box 118 shown in Fig. 23. After the sales slip carriage has been depressed as far as it will go, the carriage is retained by means of an escapement device 119 (see Fig. 25). The sales slip carried by the carriage is then in such position that a blank space on the slip opposite the printed words "Previous balance brought forward" is opposite the printing line of the adding machine printing segments 120.

The operator then reads the total check on the account carrying member and sets up the amount upon the adding machine keys 121 and pulls the adding machine handle in the usual manner. Thereafter the individual items are set up on the adding machine and the handle is pulled after each item as is usual in adding machine operations. The amount carried forward is printed on the sales slip by carbon ribbon 122 (see Fig. 15). This ribbon is carried by rolls 123, 124 and is doubled over the type segments as shown in 122a (Fig. 15). This doubling of the ribbon is done to permit a printing of the total check as will hereafter be described. Ribbon 125

108 (Fig. 29) effects the printing on the record slip.

5 The item amounts on the sales slip and record slip are printed at each actuation of the adding machine handle 125 by rocking the segments as shown in Fig. 25 through carbon ribbons and paper heretofore described against a stationary platen 130^a. The rocking of the segments is performed by 10 the adding machine printing operating mechanism which is of the type well known in the adding machine art and particularly in the Knistrom adding machine. Such an adding machine is shown in Knistrom Patent No. 1,281,792.

15 After each item amount is printed, the sales slip carriage is released by the movement of an escapement 119 controlled by the adding machine handle as will now be described. The movement of the adding machine handle 125 through link 126 and bell crank 127 rocks the main cam shaft 128 and a bell crank 131 (see Fig. 25) fastened thereto and elevates a link 132, which 20 at its upper end connects with a pivotal scape arm 133. The elevation of the link rocks this scape arm and brings a pawl 134 carried thereby into cooperation with toothed wheel 135. A pin carried by the 25 pawl 134 contacts with a pawl 135 and withdraws the pawl from escapement ratchet wheel 119. The final movement of the handle allows the parts to move backwardly and 30 allow the escapement wheel to advance one step and position the carriage for printing the next item. When a total amount is to be 35 printed on the slip the total key 137 is depressed thereby actuating a linkage 138 (see Fig. 2) and rocking shaft 139 (see Figs. 2 and 25). The shaft carries a pawl arm 140 which through a link 141 rocks a bell crank 142 against pawl 136 and withdraws it from 40 ratchet wheel 119. The wheel then turns raising the slip carriage and is finally arrested by pawl 136 engaging high tooth 45 143. The slip carriage is now in total printing position. The total printing on the sales slip and the record check is effected as heretofore described. The printing on a 50 total check slip which is to be transferred to the unit arm will now be described.

55 Referring to Figs. 15, 12 and 16 to 21, a roll of narrow paper 150 is suitably mounted as shown in Fig. 15 and the paper is lead therefrom through a guide chute 151. This guide is open at the top to present the upper edge of the paper tape in position to be gripped by the total check carriage. This carriage 152 is shown in normal position in 60 Fig. 12. It is suitably supported by rollers 153 upon a guide rail 154 so as to be free to be moved back and forth across the machine. The total check carriage carries two fixed grippers 155 and two movable 65 grippers 156 which are normally pressed

against the fixed grippers by springs 157 (see Figs. 18, 19 and 20). The carriage 152 also carries a wedge plate 158 which is provided with a pair of pins 159 engaging in a slot 160 in the lower part of guide rail 154 (see Fig. 15). At the right hand end of the slot 160 is an interference pin 161 which when the total carriage is in normal or home position is adapted to impact against one of the pins 159 and moves the wedge plate 158 so as to permit the grippers which were open upon the right-hand movement of the carriage to close and grip the paper. The carriage is moved from normal position by means of an arm 162, best shown 75 in Fig. 12, and operated from a suitable cam upon the shaft 128, which is operated by the adding machine handle. At a suitable time in the operation of the machine the arm 162 moves counterclockwise, thereby moving the carriage to the left and drawing out the paper 150. After a suitable length of paper is drawn off from the supply roll and just as the total check carriage 152 reaches the dotted line position 80 shown in Fig. 12 a shear 163 cuts off the paper. This shear is suitably operated from the shaft 128. With the carriage in the dotted line position as shown in Fig. 11, the slip of paper carried by the grippers 85 is in alignment with the adding machine type segments. (See also Fig. 21).

90 Before printing of the total is effected upon the total check slip, in order to prevent the total check slip from being torn from the grippers by the impact of the type segments, I provide means for rocking the total check carriage so as to bring the total check slip close to the impression platen 130. This is effected by means of a rock 95 shaft 164 (Fig. 12) rocked by a link cooperating with a cam on shaft 128 and having a forked arm 165 which cooperate with pins carried by the supporting guides 166 for guide rail 154 (see Figs. 25 and 12). 100

105 It will be appreciated that means must be provided for preventing the movements of the total check carriage at each operation of the adding machine handle when item amounts are being printed and to effect such operation only upon operating the handle after the depression of the total key. 110

115 Shaft 139 is rocked at each depression of the adding machine total key and this shaft carries pawl 140 (see Fig. 27) which 120 in normal position interferes with a notch 167 which is a part of the operating cams 168. These cams are attached to the shaft 128 by springs 169 so that normally the cams remain stationary and the shaft rotates. When the total key is depressed the cams are free to move in unison with the shaft (see Fig. 27).

125 After the total check carriage is rocked adjacent the platen the total is printed upon 130

the total check. This total check is now ready to be transferred to the unit arm replacing the previous total check carried therein. At the completion of the total check printing operation the old total check must be released from the unit arm and the unit arm must be in condition to receive a new total check.

Referring to Figs. 12, 16, 17 and 18, each account carrying member unit arm 71 has pivoted thereto an apertured plate 170, which plate is normally spring pressed against the unit arm by a spring 171 (see Fig. 17). The aperture permits the reading of the amount of the total check carried by the unit arm. In Fig. 17, the unit arm apertured plate is shown in closed position, in which position a check is retained therein. To open the plate and drop out the old check I utilize the rocking movement of the total check carriage. At the left hand end of shaft 164 (see Fig. 16) is fastened a disc 172 having a pin 173 adapted to contact against a downwardly extending member 174 (see Fig. 12), which member upon the rocking of shaft 164 contacts against the tail of the apertured plate (see Fig. 21) and opens up the plate to release the old total check. The plate is retained in open position by a pawl 175 which catches over the rear of the member 174, as shown by the full line position of the pawl in Fig. 21. After the aperture plate is opened the shaft 164 is rocked back to normal position, returning total check carriage to position to align with the unit arm.

To transfer the new total check to the unit arm I provide a supplementary carriage 176 (see Figs. 12 and 16) mounted on guide rails 154 and adapted at a suitable time in the operation to be moved by bell crank 177 from the full line position to dotted line position as shown in Fig. 12. In this latter position a pawl 178 pivoted on the carriage engages a notch 179 in total check carriage. Upon the return of supplementary carriage the total check carriage is carried along with it as shown in Fig. 16. Bell crank 177 eventually contacts with pawl 175 (see Fig. 21) releasing member 174 and allowing apertured plate 170 to grip the new total check. Concurrently the total check grippers 156 are opened by pin 159 contacting with a pin 180 in slot in rail 154, thereby shifting the controlling wedge plate 158 so as to open the grippers. The unit arm is now in the position as shown in Fig. 17.

In order to print the customer's name and address upon the sales slip, I provide suitable type characters 181 upon the rear of the unit arm. These type characters may represent any desired account designating data.

The final upward movement of the slip

carriage prior to printing the total amount has brought a high tooth 182 on slip carriage rack into contact with a bent plate 183 and rocked this bent plate so as to set certain parts for the address printing operation. 70

Referring to Figs. 23 and 24, the slip carriage rack 105 has a high tooth 182 which when the slip carriage moves to total position contacts with and moves a pivoted bent 75 plate 183. This plate is pivoted upon a bell crank 185 and has a pin 186 in engagement therewith and is held in contact therewith by a spring. Upon high tooth 182 contacting with bent plate 183, bell crank 80 185 is swung clockwise and by means of a roller 184 swings plate 130 clockwise and brings a roller 187 out of slot 188 and into cooperation with abutment 189. (See Fig. 23.) Upon the next upward movement of 85 plate 130 which is imparted by shaft 128, the roller 187 will be moved up, thereby rocking shaft 190 and arm 191 counterclockwise. This arm 191 has a forked end 90 cooperating with pins 192 on ends of roller 113. These pins extend into camming guide slots 193, best shown in dotted lines in Fig. 24. The movement of arm 191 from the position shown in Fig. 24 to that shown in Fig. 23 thereby concurrently rolls the 95 roller. The platen roller 113 cooperates with the carbon ribbons and the type 181 upon the rear of the unit arms and prints the customer's name and address upon the sales and record slips as shown in Figs. 30 100 and 31. In order to provide a firm backing for the unit arm during the address printing operation I provide a swinging abutment member 195 which is swung from the open to the abutment position shown in 105 Fig. 21 by means of the bell crank arm 177. The abutment is normally maintained away from the unit arm by means of a spring shown in Fig. 21 to permit the reading of the number on the total check. 110

The movement of addressing roller arm 191 through a pin 196 and sloping slot in plate 197 is adapted to operate cutting off knife 117 and cut off a previously printed record check. The cut off check thereafter 115 drops in box 118 where it is retained.

Upon the completion of the address printing plate 130 returns to normal position under the influence of a return spring 198.

After the address printing operation is completed escapement pawl 136 is released from first high tooth to second high tooth shown in Fig. 25. This permits the slip carriage to move to extreme upper position and feed forward the record check paper 125 through the knives 116 and 117 and thereby space the record checks apart so that the customer's name and address is not severed by the knives on subsequent cutting of paper. Just prior to the aforesaid final 130

movement of the slip carriage, the supplementary carriage 176 has been moved to the left to the position shown in Fig. 16. The end wall of the total check carriage has impacted against a spring pressed plunger 200 and forced this plunger to the left and by means of the pointed end thereof has cammed the unit arm retaining pawl 96 to such position as to release the unit arm and 5 permit it to return to position in the accounting section. In Fig. 16 the arm is shown in position in the computing section just prior to its return to the accounting section. 10 After the unit arm is released the slip carriage moves to extreme upper position bringing a pin 201 shown in Figs. 29 and 28 into contact with a pivoted member 202, thereby rocking pawl 178 out of notch 179 15 in total check carriage 153. The total check carriage is then returned to normal position by means of a spring 203 (see Fig. 12). Pivoted member 202 through a link 203^a connects with the pivoted bail 204 20 which carries locking plate 82, thereby releasing locking plate 82 from engagement with the notch in bar 78 (see Figs. 10 and 28).

To restore the parts in the accounting section the end of shaft 128 is provided with a cam 205 which through a bell crank draws down a link 206 and rocks shaft 91. To this shaft is fastened a dog 207 (see Fig. 12) which upon rocking clockwise contacts with 25 a pin 208 and rocks arm 89 clockwise, restoring parallel bar 86 to normal position. Pawl 209 carried by this arm contacts against a roller 210 carried by forked arm 211, thereby rocking forked arm clockwise 30 and through a pin 212, restoring latch arm 83 to normal position in which it is latched by pawl 77^a. Parallel bar 86 also latches over 35 as shown in Fig. 9. Inasmuch as pawls 77 and 77^a are connected to bail 204 by means of springs 213 and 214 (see Figs. 13 and 14), these pawls will not be drawn up into latching position until bail 204 is 40 raised at the end of the series of operations in the computing section. Therefore 83 45 will not be latched by 77^a except after the operations in the computing section have been completed. When bail 204 is rocked and plate 82 is lifted from the notch in bar 78, the bar 78 will be drawn to the 50 right under the tension of spring 84 which is put under tension by the rocking of member 83 to which it is attached. Spring tension of spring 84 overcomes the tension of spring 79 which is a light spring. This bar 55 78 will then be locked in normal position by pawl 77 and the unit arm carriages will then return to normal position under the influence of springs 69. Previous to this return of the carriages the unit arm which 60 65 was in the computing machine had com-

pletely returned to normal depending position.

It has been found that the unit arms in returning have a tendency to rebound from vertical depending position. In order to 70 prevent this undesirable action and at the same time provide means for removing any desired unit arm for repair or for the replacement of another set of type 181, designating a different name or revised address. 75 I provide the construction illustrated in Figs. 6, 7 and 9. Each unit arm 71 has at its upper end two metal plates 71^a and 71^b which are notched at the side to receive the supporting shaft 70. Below this shaft is 80 a cross bar 215 which is suitably fastened to the unit arm carriage bracket 64 and 64^a. This cross bar is stiffened by plates 216 which tie it to the shaft. Cross bar 215 is grooved upon its lower edge as shown at 85 217 and is provided with a resilient bumper block 218. Each unit arm carries a retaining pawl 219 which is free to move endwise to a limited extent on the unit arm and which has a projection adapted to cooperate with groove 217. Over the shaft 70 is slipped a retaining fork 220 which through a spring 221 connects with retaining pawl 219. Retaining fork has a projection 222 to permit the fork to be gripped and raised when it is desired to replace the unit arm. Upon the return of the arms to vertical position the resilient bumper 218 takes up a part of the shock. Thereafter 90 the spring pulled retaining pawl 219 engages in groove 217 and locks the arm in vertical position, thereby preventing the objectionable rebound. The complete cycle of operation having been traced for one operation, it is sufficient to state briefly that 95 credit operations can also be performed. The adding machine is provided with a credit key usually known as a subtracting key. This is shown at 137^a in Figs. 2 and 100 1. In a credit transaction the index arm is first selected and positioned in visible position in the computing section. The customer's name and other data is written on the sales slip and the amount of the account is set forth on the adding machine keys. 110 Thereafter the amount to be paid or subtracted is set up, the credit key depressed and the machine operated in the usual manner. This operation prints the sales slip as 115 shown in Fig. 33 printing on the slip the item R, indicating the amount is a received amount. The subtraction is carried out and the new amount or subtrahend, i. e. new amount of account, is printed on the slip and transferred to the unit arm in the 120 usual manner.

In Fig. 32 I have shown the sales slip which is the duplicate slip, which is used by the clerk as a guide in setting up the item amounts as slotted. This slip is not 125 130

placed in the machine and receives no printing. The slot, however, permits the record slip shown in Fig. 31 to be inserted in their respective slips for convenience in filing. 5. These slips can be referred to at a later date should the customer or the storekeeper desire any data not given by the record slip or as sales slip alone.

While I have described one method of 10 operating my improved machine and the general business system utilized with it, it will be understood that the use of the machine is not limited to retail stores or any particular business, but the machine has a 15 wide application where it is desired to preserve a record or account of numerical transaction, which change in amount by additions or subtractions of new quantities from time to time. 20 If desired the slip printing of the item amounts may be omitted and the total check alone can be printed or if desired the machine may be used in pay roll work for 25 totalizing the pay accounts of the individual employes and for addressing and printing the total amount upon the pay envelopes. These and other applications of my invention will not be discussed in detail.

I claim:

- 30 1. In a device of the class described, an accounting section, a computing section, a plurality of printed accounts carried by the accounting section, and means associated with the computing section for replacing 35 said printed accounts with revised printed accounts whereby the current state of each account is available in the accounting section.
- 40 2. In a device of the class described, an accounting section, a computing section, account carrying members in said accounting section, means for selecting a member carrying a particular account from the accounting section and displaying the account to the 45 operator in a position in which said member is in cooperative relation to the computing section, and means associated with said computing section for transferring an account to said member, and means for returning the member to the accounting section.
- 50 3. In a device of the class described, an accounting section having a plurality of account carrying members therein, a computing section comprising a printing mechanism, means for selecting a particular account carrying member from the accounting section and for moving said member to a cooperative position in the computing section, 55 means for transferring a check carrying an amount printed in said computing section to the account carrying member whereby a revised amount of the account may be carried by the accounting member.
- 60 65 4. In a device of the class described, an

accounting section, a computing section, a plurality of account carrying members in said computing section, each of said members carrying a paper total check record of the status of the account, means for selecting 70 a particular account carrying member and for displacing the same to reading position, means for setting up the amount thus displayed in the computing section, means for altering the said setting in accordance with 75 the amount of a new transaction, and means for transferring to the account carrying member a record on a paper total check of the amount thus obtained whereby the account carrying member displays the revised status 80 of the account.

5. In a device of the class described, a plurality of account carrying members, means for selecting one of said members and for moving it to such position as to display 85 the account and to afterwards receive a revised account, a computing section having means adapted to receive the amount of the account thus displayed and additional items, and effect a summation thereof, manually operated means for setting up said displayed account, amount and items in the computing section, and means for transferring the result or total as obtained by the computing 90 section to the account carrying member. 95

6. The invention set forth in claim 5 in which the computing section is provided with means for printing the result or total upon a slip of paper which slip is transferred to the account carrying member to 100 thereby form the record of the account as carried by the member.

7. In a device of the class described, in combination, an accounting section, a plurality of account carrying members therein, each said member carrying a total check representing by printed characters the current status of each account, a computing section, means for selecting a particular account carrying member and for displacing 110 the same to reading position, means for setting up the amount thus displayed in the computing machine, means for altering the setting in accordance with the amount of a new transaction, and means for printing the 115 result thus obtained upon a total check and for transferring the check to the account carrying member whereby said member displays the revised status of the account.

8. The invention set forth in claim 7, in 120 which means is provided to release the old total check from the account carrying member.

9. The invention set forth in claim 7 in which means is provided for releasing the 125 old total check from the account carrying member and for thereafter gripping the new total check.

10. In a device of the class described, an accounting section, a computing section, a 130

- plurality of account carrying members in said accounting section, means for selecting a particular account carrying member and for displacing the same to reading position, 5 means for setting up in the computing section the amount of the account thus displayed, means for printing this amount upon a sales slip, means for printing amounts on said slip corresponding to the written items 10 thereon, means for printing a total of the amount first printed and the item amounts on the sales slip.
11. The invention set forth in claim 10 in which type is provided on the account carrying members representing account designating data, and in which means is provided for printing said data upon the sales slip.
12. The invention set forth in claim 10 in which means is provided for printing the data corresponding to the printed data on the sales slip upon a duplicate record check.
13. The invention set forth in claim 10 in which the account carrying members carry 25 type representing account designating data and in which means is provided for printing said data upon the sales slip and upon the duplicate record check.
14. The invention set forth in claim 10 in which means is provided for printing a total 30 check corresponding in amount to the total as shown on the sales slip, and having means for transferring said check to the account carrying member whereby the amount of the total check furnishes data corresponding 35 to the status of each account.
15. The invention set forth in claim 10 in which means is provided for printing a total check corresponding to the total upon 40 the sales slip, and in which means is provided for displacing the old total check designating the past account from the account carrying member and for replacing said old check with the new total check 45 whereby the account carrying member carries a printed check showing the status of the account after the transaction.
16. In a device of the class described, in combination, an accounting section, a plurality of account carrying members therein, each of said account carrying members being provided with type carriers representing account designating data, a computing section and means in said section for printing a 50 record of the account designating data as carried by any one of the account carrying members.
17. The invention set forth in claim 16 in which the account designating data represents the name and address of the customers.
18. In a device of the class described, in combination, a plurality of independently 60 movable unit arms, each of said arms being provided with type representing arm designating data, a printing mechanism, means for selecting any one of the aforesaid unit arms and for displacing the same in cooperative relation with the printing mechanism, said printing mechanism being thereafter 70 adapted to record the data carried by the type on the unit arm.
19. In a device of the class described, a plurality of type segments, a total check carriage, means associated with said carriage for gripping, drawing off and shearing a strip of paper, means for positioning the check thus produced adjacent the type segments, means for printing thereon the amount set up on the segments, means for 75 releasing the printed check and means for returning the carriage to regrip the strip of paper.
20. In a device of the class described, in combination, a total check carriage having 80 provision for gripping, drawing and shearing a strip of paper and for presenting the check thus produced to the type segments so as to receive a printed impression therefrom, a supplementary carriage adapted to connect with the total check carriage and transfer the check to a check receiving mechanism, means for disconnecting said carriages, and means for returning the total check carriage to a position to regrip the paper strip. 85
21. In a device of the class described, in combination, a total check carriage, an account carrying member adapted to carry a total check, a supplementary carriage adapted to be locked to the total check carriage 90 and to move in unison therewith and effect the transfer of the check from the total check carriage to the account carrying member, and means for releasing said lock after the parts have assumed the proper position 100 to effect the transfer.
22. In a device of the class described, in combination, a computing section, an account carrying member adapted to be displaced into cooperative relation with said machine, means for locking said member in said position, a total check carriage adapted to carry a total check into cooperative relation with said member, means for gripping the new check and means for thereafter 110 releasing the lock which retains the account carrying member.
23. In a device of the class described, in combination, a computing section, an accounting section, a plurality of account carrying members therein adapted to be individually displaced into cooperative relation with the computing section, means for locking the displaced member in said position, and means for releasing the said lock upon 115 the completion of the computing operation.
24. In a device of the class described, in combination, a computing section, an accounting section, a plurality of account carrying members therein adapted to be indi- 120
- 65 125
- 130

ividually displaced into cooperative relation with the computing section, means for locking the accounting section upon a member being thus displaced, and means for releasing said lock upon the completion of the computing operation.

25. In a device of the class described, in combination, an accounting section comprising an index, a plurality of index arms, a plurality of unit arms arranged in paired groups, means operable upon the sliding of the index for selecting a group and for thereafter moving said group of arms in unison to bring a particular arm to operating position, means operable upon the displacing of the index arm for displacing the previously selected unit arm and means for locking the other arms against movement by the depression of the index arm.
- 20 26. In a device of the class described, in combination, a plurality of pairs of unit arm carriages, a plurality of unit arms therein, a plurality of index arms, there being one arm for each pair of unit arm carriages, means for moving one of said carriages upon the sliding of an index arm to thereby bring a particular unit arm to operating position, means for displacing the previously selected arm and means for locking the remaining unit arms and index arms against movement.

27. In a device of the class described, in combination, an accounting section, a plurality of unit arm carriages therein, said carriages being arranged in pairs, a plurality of index arms, one for each pair of carriages, a plurality of pairs of supplementary index arm carriages therein being one pair for each pair of unit arm carriages, and means operable upon the sliding movement of an index arm for locking a supplementary carriage to the unit arm carriage whereby the unit arm carriage is moved in unison with the index arm.

45 28. In a device of the class described, an accounting section having in combination a plurality of groups of unit arms, each said arm forming an account carrying member, means for selecting a particular group of unit arms and for thereafter selecting a particular arm from the previously selected group, means for preventing the selection of a second arm after a particular arm has been selected and means operable by the first named means for displacing to reading position the previously selected arm.

29. In a device of the class described, a plurality of pivotally mounted unit arms, each said arm forming an account carrying member, means for selecting any desired unit arm, and means operable by the movement of the aforesaid selecting means for swinging the selected arm pivotally to a reading position.

65 30. In a device of the class described, a

plurality of unit arms, means for selectively positioning any one of said arms to operative position, each said arm having a pivoted plate thereon adapted to retain a slip of paper between the plate and the arm, and an aperture in said plate adapted to permit the reading of the amount on the slip of paper.

31. In a device of the class described, a plurality of unit arms, means for selectively positioning any one of said arms to operative position, each said arm having means for replaceably carrying a paper account record and having on said arm type representative of account designating data.

32. In a device of the class described, a carriage, a supporting shaft carried by said carriage, a plurality of unit arms pivotally mounted upon said shaft, means for selectively displacing any one of said arms to reading position, and means for retaining said arms normally in position upon said shaft but permitting the release of any arm therefrom for replacement.

33. In a device of the class described, a unit arm carriage, a plurality of unit arms pivoted therein, means for preventing the accidental swinging of the said arms, said means being also adapted to prevent the rebound of an arm when it swings back to its displaced position.

34. In a device of the class described having a computing section and comprising in combination with an adding machine, a substantially flat rectilinearly movable sales slip carriage with provision for receiving a rectangular sales slip in substantially flat position therein, means for manually setting the said carriage to receive the first printed impression from the adding machine, means for thereafter automatically advancing the carriage rectilinearly to receive additional impressions upon the sales slip carried thereby, means for printing amounts upon said sales slip and concurrently controlling the rectilinear movement of the slip carriage so that successive printed amounts appear opposite the respective successive written items, and means for printing a total of the itemized amounts and of the accounts carried forward.

35. The invention set forth in claim 34 in which means is provided for duplicating the printed record from the sales slip upon a record check.

36. The invention set forth in claim 34 in which means is provided for printing a duplicate record of the printed record on the sales slip upon a record check and for also printing a separate total check showing only the total of the items printed upon the sales slip.

37. In a machine of the class described, in combination, a plurality of account carrying

members, a computing section including an adding machine adapted for the addition and subtraction of amounts, means for selecting a particular account carrying member and thereafter for moving it to a predetermined distinctive position remote and distinct from the other non-selected accounts in which the account carried by the selected member will be individually and distinctively displayed separately from the non-selected accounts, means for setting up the amount visually displayed in the adding machine and for thereafter setting up therein other amounts which are to be added or subtracted from the particular account selected, and means for transferring the result of the computation to the selected account carrying member.

38. The invention set forth in claim 37 in which the transferring operation displaces the past account as carried by the account carrying member.

39. The invention set forth in claim 37 in which the account itself represented by amount characters on a slip of paper carried by the account carrying member and in which the displacing of the past account is effected by the substitution in the account carrying member of a second slip of paper having characters thereon representing the revised status of the account.

40. In a machine of the class described, in combination, a plurality of account carrying members having provisions for representing the status of an account by amount characters on a slip of paper carried thereby, a computing section including an adding machine adapted for the addition and subtraction of amounts, means for selecting a particular account carrying member and for moving it to such position as to display the account carried thereby, means for setting up the amount visually displayed in the adding machine and for thereafter setting up therein other amounts which are to be added or subtracted, and means for transferring the result of the computation to the account carrying member by the substitution therein of a second slip of paper having characters thereon representing the revised status of the account.

41. In a machine of the class described in combination, a plurality of account carrying members, a computing section including an adding machine adapted for the addition

and subtraction of amounts, means for selecting a particular account carrying member and for moving it to such position as to display to the operator the account carried thereby, means for setting up the amount thus visually displayed in the adding machine and for thereafter setting up therein other amounts which are to be added or subtracted from the particular account selected, and means for first displacing entirely the past account as carried by the selected member and for thereafter transferring thereto the result of the computation performed by the adding machine.

42. In a device of the class described, having a computing section comprising in combination an adding machine, a sales slip carriage means operable by the operation of the adding machine for successively printing item amounts upon the slip carried by the carriage, means for advancing the carriage step by step so as to print successively item amounts upon successive lines on said slip, means for printing a total upon said sales slip, and means associated with said total printing means for advancing said carriage to a predetermined position prior to the impression of the total print, said last mentioned means having provisions for effecting said advance in variable extents to said predetermined position and irrespective of the number of item amounts printed whereby the total imprint is always located at the same point upon the sales slip.

43. In a device of the class described, in combination, an accounting section, a plurality of members therein, each being provided with type carriers representing account designating data, a computing section including an adding machine, a slip carriage, means for printing item amounts set up in the adding machine upon the slip carried thereby, means for moving the slip carriage so that successive item amounts are imprinted upon successive lines upon said slip, means for printing a total upon said slip, means for selecting a member in the accounting selection and displacing the same into the computing section, and means for printing the account designating data from the type carried by the selected member upon the slip.

In testimony whereof I hereunto affix my signature.

JOSEPH V. WECKBAUGH.
